CARTON OPENING AND HANDLING DEVICE
Ralph G. Borchetta, Jr., Harrison, N.Y., and John J. Bogdanski, Joseph V. Kubovy, and James E. Mulread, Stamford, Conn., assignors to Pitney-Bowes, Inc., Stamford, Conn., a corporation of Delaware
Filed June 13, 1962, Ser. No. 202,263
15 Claims. (Cl. 30—2)

The present invention relates to a device for operating upon closed cartons and more particularly to such a device which opens each carton by separating a wall thereof formed by flaps releasably secured together.

In many States it is required that a tax stamp be applied or imprint be made on each package of cigarettes to be sold within the State. The packages are packed in a closed carton of the type having a wall formed by bending inwardly flaps formed by extensions of the side wall and releasably securing the flaps together. To expose the bottoms of the respective cigarette or other packages for access thereto by the stamp or imprint applying means this wall is opened by separating and bending open the flaps. It is thus essential for subsequent operations that include the stamp affixing and reclosing operations that the carton be opened by the separating of the flaps, that such separation of the flaps be with a minimum of mutilation, if any, of the flaps, and that the flaps after being opened be presented in a condition which enables the flaps to have glue applied thereto and then be folded into their initially closed position. If the wall is formed of a narrow flap and a wide flap, as is generally the case, it is also necessary that each carton be properly oriented to have the same flap be on the same side of the carton.

It is accordingly an object of the present invention to provide a device for opening cartons which performs the above essential steps in opening a carton or else prevents the carton from passing through the device.

Another object of the present invention is to provide for opening a carton by severing the releasable detachable connection of the flaps forming the wall with a minimum of mutilation of the flaps.

A further object of the present invention is to provide in a device of the above-noted type a means for normally preventing passage of any carton therethrough unless it has its flaps both properly opened and properly oriented in the device.

Another object of the present invention is to provide in a carton opening device for effecting reverse bending of the flaps from their initial closed condition for enabling subsequent operations on the carton, such as reclosing, to be effectively accomplished.

A feature of the present invention resides in guiding each carton along a path to engage a nose portion of a flap opening means so that with subsequent movement the nose portion is projected between the bowed wall of the carton that is to be opened and the carton proper. As the top wall is formed of two flaps releasably secured together and as the nose portion increases in height rearwardly it causes the releasable securement between the two flaps to be broken and the flaps separated. However, to prevent undue strain on the flaps by the nose portion, there is mounted rearwardly of the nose portion a laterally extending thin edge blade that is caused to enter between the overlying segments of the two flaps and to sever any releasable connection or glued portions remaining between the flaps of the carton that were not previously broken apart by the nose portion. Thus mutilation of the flaps is prevented.

The nose portion and blade are mounted on a shoe means that after the blade includes a first laterally extending surface which flares rearwardly outwardly and by

2

engaging the large flap causes it to be reversely bent from its initial position. Similarly, the small flap by another rearwardly laterally flaring surface formed on the shoe means is also caused to be reversely bent and thus the carton leaves the device with the flaps opened and properly positioned for subsequent operations.

In order to make certain that the device has functioned properly on each carton, there is provided blocking means which normally block the path of the carton through the device. However, for releasing the blocking means to permit a properly opened carton to pass therethrough, there is provided flap sensing means which is mechanically connected to the blocking means and if the carton is correctly oriented and the flaps are properly opened, the sensing elements mechanically render the blocking means ineffective to block the carton and hence the carton passes through the device.

Other features and advantages will hereinafter appear. In the drawing:

20 FIG. 1 is a plan view of the carton handling device of the present invention, with portions broken away to show underlying details of construction.

FIG. 2 is a front elevational view thereof, partly in section and with portions broken away.

25 FIG. 3 is a side view, with portions also broken away. FIG. 4 is a sectional view taken along section line 4—4 of FIG. 1 showing the initial bowing of the wall of the carton which is to be opened and with the nose portion thereunder.

30 FIG. 5 is a sectional view taken along section line 5—5 of FIG. 1.

FIG. 6 is a detail view showing the initial severing and separating of the flaps of the wall.

FIG. 7 is a sectional view taken along section line 35 7—7 of FIG. 6.

FIG. 8 is a detail view showing the flaps opened and reversely bent as the carton leaves the device of the present invention.

40 FIG. 9 is a plan view showing details of the carton blocking mechanism with the parts being shown in carton blocking position.

FIG. 10 is a plan view similar to FIG. 9 showing the parts in their non-blocking or carton passing position.

45 FIGS. 11, 12 and 13 are perspective views of individual parts of the carton blocking mechanism.

Referring to the drawing, the carton opening device of the present invention is generally indicated by the reference numeral 20 and includes a base enclosure 21 provided with foot members 22 and 23. The enclosure has 50 a vertical bearing 24 in which is positioned a cylindrical support member 25 connected at its lower end to linkage elements 26 and 27 while a horizontal plate 28 is secured on its upper end. Also secured on the base enclosure 21 is a side wall 29 whose vertical side surface with the top surface of the horizontal plate 28 define a path for guiding a carton 30, shown in dotted lines. For maintaining the carton against the side wall 29 there is provided spring urged rollers 31. It will be appreciated that movement of the linkage elements 26 and 27 serves 60 to adjust the elevation of the plate 28 on the base member and provides for accommodating cartons having different heights.

The carton 30, in the embodiment herein disclosed, has a wall 30a formed by a wide flap 30b folded over 65 a narrow flap 30c with releasably securing means such as glue spots 30d, FIG. 1, maintaining the flaps together and the carton closed.

As shown in FIGS. 2 and 3, an inverted, somewhat U-shaped support 32 is mounted on the base enclosure 21 70 and includes a forward extension 33 which mounts means for engaging a longitudinal corner edge 30e of the carton to cause the wall 30a to be bowed for reasons which will

be hereinafter apparent. The bowing means includes a somewhat conical roller 34 which, as shown in FIG. 2, is rotatably mounted on a pin 35 that is secured at its upper end in a cylindrical plug 36. A downwardly depending tube 37 is also secured to the plug 36 for cooperation with a bushing portion 38 of the conical roller while a spring 39 between the plug 36 and bushing portion 38 urges the conical roller downwardly. It will be seen that the conical roller 34 may thus move vertically against the action of spring 39 and thus the roller may exert a variable bowing force depending upon the rigidity of the carton thereby maintaining the desired amount of force to be exerted on the corner edge 30e of the carton to effect the bowing of the wall 30a of the carton.

Moreover, according to the present invention, the conical roller may be laterally moved toward and away from the side wall 29 in order to enable adjustment for different sizes of cartons. This is accomplished by providing a threaded aperture 40 in the plug 36 into which a screw 41 is threaded to thereby support the plug by the forward extension 33 with the threaded aperture 40 being eccentric to the pin 35 which is secured on the axis of the cylindrical plug 36. It will thus be appreciated that the cylindrical plug 36 and pin 35 may be pivoted and positioned about the axis of the screw 41 and that such movement will effect lateral movement of the conical roller 34 with respect to the side wall 29.

In carrying out the present invention after the wall 30a of the carton has been bowed, the carton is advanced against a shoe means generally indicated by the reference numeral 42 which has a forward nose portion 43 which, as shown in FIG. 4, enters beneath the bowed wall 30a and particularly eccentric to the wall 30a to be under the wide flap 30b of the carton. The nose portion 43 flares laterally and vertically rearwardly thus increasing its cross-sectional dimension and as the carton is advanced along its path through the device, the nose portion serves to stress the wall 30a until sufficient force is present to separate the flaps held by the glue spots 30d. However, according to the present invention, in order to prevent undue strain with possible mutilation of the flaps there is provided a blade 44 secured on the shoe means rearwardly of the nose portion. This blade 44, as shown in FIGS. 6 and 7, enters between the overlying portions of the narrow and wide flaps 30b and 30c of the wall and serves to sever any glue spots 30d that remain between the flaps that have not been previously broken apart by the nose portion. The blade is formed of thin material and has a thin forward edge 45 that increasingly extends laterally toward the side wall 29 as it extends rearwardly to thereby extend substantially through the overlying portions of the flaps where any glue spots would be or are present. The blade also, as shown in FIG. 5, has an upper surface 46 that flares upwardly as it extends rearwardly to guide the flap 30b toward an open position.

As shown in FIG. 1, the blade 44 is secured to the shoe means 42 by being made fast in a recess 47 in the shoe means in order to have its leading outer surface and the adjacent surface of the nose portion present a smooth surface rearwardly.

The shoe means rearwardly of the blade 44 has an upper surface 48 that increases slightly in height as it extends rearwardly with its bottom surface 49 remaining flat until a vertical pylon portion 50 is reached when there is a sharp increase in height. The pylon portion 50 has screws 51 threaded therein for securing the shoe means to a rearward extension 52 of the bight portion of the support 32. Formed on the shoe means slightly in advance of the pylon portion 50 is a straight lateral edge surface 53 that flares toward and beyond the side wall 29. The leading part 53a of the edge surface 53 forces the narrow flap to a substantially vertical position while the rearward part 53b of the edge surface 53 forces the narrow flap to be reversely bent 180° from its initial carton closing position to extend outwardly horizontally from the carton path, as shown in FIG. 8. Similarly, the wide flap is reversely bent 180°

from its carton closing position by a lateral edge surface 54 formed on the shoe means on the other side of the carton path which flares rearwardly divergently from the side wall 29 and forces the wide flap to its reversely bent position where it extends substantially horizontally outwardly of the carton path.

It will thus be appreciated that the carton 30 is initially caused to have its wall 30a bowed by the conical roller 34 by the latter exerting a force against the corner edge 30e and that as the carton is moved along a path defined by the plate 28, the side wall 29, the rollers 31 and the conical roller 34, the nose portion 43 of the shoe means enters beneath the bowed wall 30a and as the nose portion increases in height, it breaks the glued connection 30d between the narrow and wide flap 30c and 30b. Moreover the present invention provides for inserting between the overlying portions of the narrow and wide flaps the blade 44 to sever any unbroken glue connection before the nose portion exerts an excessive force that would tend to mutilate the flaps and carton. It is of course appreciated that if desired, the nose portion may be made so that it does not increase sufficiently in cross-sectional area before the blade 44 so that the blade does all the severing of the glue connection.

25 As the carton further advances along the path the narrow flap 30c engages the edge surface 53 which initially forces it to a vertical position and then forces it to a horizontal outwardly extending reversely bent position. Similarly the wide flap 30b is caused to be reversely bent as it moves through the device by the edge surface 54 to thus provide a carton that has been opened with the flaps extending outwardly therefrom and with a minimum if any mutilation of the flaps.

30 The device of the present invention provides for normally blocking passage of a carton along the path but for releasing the blocking to permit the carton to pass if the carton has its flaps properly oriented, i.e. the narrow flap is at the side of the path defined by the side wall 29. Moreover, the blocking means prevents passage of the carton if the flaps have not been opened to a predetermined position which may occur if the carton is misoriented in the machine or if the nose portion has not entered beneath the bowed wall. To this end there is provided a blocking member 55, as shown in FIGS. 9 and 10, which is mounted for movement in and out of the carton path in a cutout 56 formed in the side wall 29 at its rearward end portion slightly above the plate 28. The blocking member 55 is pivotally secured to a link 57 that is fast on a shaft 58 pivotally mounted on bosses 59 formed on the side wall 29. It will thus be seen that rotation of the shaft 58 effects the lateral movement of the blocking member in and out of the carton path. Also secured on the shaft for movement therewith is a small flap detector 60 shown in FIG. 13 having an arm 60a that is mounted to normally project into the carton path to be engaged by the upwardly extending small flap. A spring 61 encircles the shaft 58 and has one end portion 61a engaging a corner 60b of the detector 60 and its other end portion secured as at 62 to the side wall 29 and is employed to exert a clockwise urging to the detector 60 and shaft 58 to normally urge the blocking member into blocking position shown in FIG. 9 and the arm 60a into the carton path. However, upon passing of a carton that has its flaps properly oriented and opened, the leading edge of the narrow flap will engage the arm 60a causing counterclockwise rotation to the position shown in FIG. 10 wherein the blocking member has been retracted from the carton path and thus the carton is permitted to pass through the device. If of course there is no flap to engage the arm 60a, as would happen if the wall 30a were not opened, then the blocking member would prevent passage of the carton.

65 In the event that the wall is opened but that the carton is not properly oriented, i.e. the wide flap 30b is against the side wall 29, then the blocking mechanism of the present invention includes a large flap detector 63 (shown

in FIG. 12) that is freely mounted on the shaft 58 and has an arm 63a that projects into the carton path but in advance of the arm 60a of the small flap detector 60 and spaced higher in the path than the arm 60a. Another arm 63b of the wide flap detector carries a pin 63c which cooperates with an interferer 64 (shown in FIG. 11) pivoted as at 65 to the side wall 29. The interferer 64 is formed with a slot 64a in which the pin 63c is positioned and at its end is formed with a downwardly extending lip 64b that is movable to abut an upwardly projecting pin 10 60d of the small flap detector. A spring 66 connected between the interferer 64 and the large flap detector 63 urges the large flap detector clockwise to have its arm normally positioned in the carton path and the interferer 15 counterclockwise to the positions shown by full lines in FIGS. 9 and 10.

If a wrongly oriented carton i.e. where the wide flap is nearest the side wall 29, has its flaps opened and is moved along the path the large flap 30b will initially engage the large flap detector arm 63a causing a subsequent 20 counterclockwise movement thereof, which movement imparts, through the pin 63c and elongate slot 64a, a clockwise movement of the interferer 64 from the full line position to the dotted line positions shown in FIG. 9. At the dotted line position, the lip 64b is placed in the path of movement of the pin 60d and the small flap detector 60 is prevented from rotating by the pin 60d abutting against the lip 64b. Accordingly the carton is prevented from passing through the path as the blocking member is not removed from the path and the carton will engage it as indicated by the dotted line carton in FIG. 9.

It will be understood that with the instant device, if a carton is properly oriented that the small flap will not trip the wide flap detector as the arm 63a of the detector is spaced upwardly in the carton path beyond where the small flap would engage it and on the same side of the path but will effect rotational movement of the small flap detector and subsequent unblocking of the carton path. In the event that the nose and shoe means have failed to properly open a carton, the small flap detector will not be encountered by a small flap and hence the blocking member will maintain the carton path blocked. For the condition where an unproperly oriented carton has its wide flap against the side wall 29, the wide flap will engage the large flap detector and cause movement of the interferer to block the releasing movement of the small flap detector and hence the blocking member will continue to block the carton path and prevent movement of the carton therethrough.

Since many changes could be made in the embodiment of the invention as particularly described and shown herein without departing from the scope of the invention, it is intended that this embodiment be considered as exemplary and that the invention not be limited except as warranted by the following claims.

The invention claimed is:

1. A device for operating upon a carton having a wall formed by a first flap overlying and releasably secured to a second flap to separate said flaps and open the carton; comprising means for maintaining the carton with the 60 wall exposed,

shoe means having a leading nose portion,

means for relatively moving the shoe means with respect to the carton for projecting the nose portion under the wall,

and blade means secured to the shoe means rearwardly of the nose portion and extending laterally beyond the nose portion for entry between the two flaps to sever any releasable connection theretwixen.

2. A device for operating upon a carton having a wall formed by a top flap having a portion overlying and releasably secured to a bottom flap to separate said flaps to open the carton and with one lateral end of the wall being free;

comprising means for longitudinally guiding a carton 75

along a path with the wall being exposed and with the free end leading,

shoe means positioned in the path and having a nose portion projectable into the free end of the carton only under the top flap,

and blade means secured to the shoe means rearwardly of the noses portion, said blade means having a thin front edge that extends substantially laterally of the nose portion and is projectable between the overlying portions of the two flaps to sever any releasable connection theretwixen.

3. A device for operating upon a carton having a wall formed by a wide flap overlying and releasably secured to a narrow flap to separate said flaps to open the carton; comprising means for longitudinally guiding a carton along a path with the wall being exposed,

shoe means positioned in the path and having a leading nose portion aligned with the path and projectable under the wide flap,

and blade means secured to the shoe means rearwardly of the nose portion, said blade means being formed to provide a thin front edge that extends laterally and rearwardly from the nose portion and an upper surface that flares upwardly as it extends rearwardly from the nose portion for entry between the two flaps to sever any releasable connection theretwixen and urge the flaps to be separated.

4. A device for operating upon a carton having a wall formed by a wide flap having a portion overlying and releasably secured to a narrow flap to separate said flaps to open the carton and with one lateral end of the wall being free;

comprising means for longitudinally guiding a carton along a path with the wall being exposed and with the free end leading,

means engaging the carton for bowing the wall, shoe means positioned in the path and having a nose portion projectable into the bowed free end of the carton only under the wide flap,

and blade means secured to the shoe means rearwardly of the nose portion, said blade means being formed to provide a thin front edge that extends laterally and rearwardly from the nose portion and an upper surface that flares upwardly as it extends rearwardly from the nose portion for entry between the overlying portion of the two flaps to sever any releasable connection theretwixen and to urge the flaps to be separated.

5. A device for operating open a carton having a wall formed by a wide flap releasably secured to a narrow flap to separate said flaps and open the carton;

comprising means for longitudinally guiding each carton along a path,

means for opening said flaps,

blocking means normally positioned in said path for preventing movement of a carton theretwixen but movable therefrom to a non-blocking position to permit movement of a carton therethrough,

means positioned in said path after the opening means for sensing the orientation of the wide and narrow flaps,

and means mechanically interconnecting the blocking means and the sensing means for moving the blocking means to its non-blocking position upon the sensing of only the opening and correct orientation of the wide and narrow flaps.

6. A device for operating upon a carton having a wall formed by a wide flap secured to a narrow flap to separate said flaps and open the carton;

comprising means for longitudinally guiding each carton along a path,

means for opening the flaps and urging them upwardly in the path,

able therefrom to a non-blocking position to permit movement of a carton therethrough,
means positioned in said path after the opening means for sensing the position of the narrow flap and including a movably mounted arm extending into the path to be engaged and moved by the narrow flap out of said path,
and means mechanically interconnecting the blocking means and the narrow flap sensing means for moving the blocking means to its non-blocking position upon movement of the arm out of the path.

7. A device for operating upon a carton having a wall formed by a wide flap secured to a narrow flap to separate said flaps and open the carton;

comprising means for longitudinally guiding each carton along a path,

means for opening the flaps and urging them upwardly in the path,

blocking means normally positioned in said path for preventing movement of a carton therewith but movable therefrom to a non-blocking position to permit movement of a carton therethrough,

wide flap sensing means positioned in said path after the opening means and mounted for movement upon engaging only the wide flap,

flap sensing means positioned in said path after the wide flap sensing means and mounted for movement upon engaging either flap,

blocking means interconnecting the wide flap sensing means and the flap sensing means for preventing movement of the flap sensing means upon movement of the wide flap sensing means,

and means mechanically interconnected to the flap sensing means and the first mentioned blocking means for moving the latter to its non-blocking position upon movement of the flap sensing means.

8. The invention as defined in claim 7 in which the wide flap sensing means and the flap sensing means each includes an arm normally positioned in the path with the arms being mounted to extend into the path from the same side of the path with the wide flap sensing means arm being higher in the path than the flap sensing means arm.

9. A device for operating upon a carton having a wall formed by a wide flap releasably secured to a narrow flap to separate said flaps and open the carton;

comprising means for longitudinally guiding said cartons along a path,

means for opening the flaps and urging them upwardly in the path,

a first arm pivoted for movement on one side of the path after the opening means for movement in the path,

a second arm pivoted after the first arm and on the same side of the path for movement in and out of the path, said first arm being spaced higher in the path than the second arm,

a blocking member mounted for movement in and out of the path,

linkage interconnecting the blocking member and the second arm whereby movement of the second arm out of the path moves the blocking member out of the path,

and interfering means connected to the first arm and mounted for movement to an interfering position by movement of the first arm rearwardly to thereby prevent movement of the second arm.

10. A device for operating upon a carton having a pair of spaced side walls and a connecting wall formed by a flap of each side wall being bent to converge and have portions overlying each other that are releasably secured together to separate said flaps to open the carton;

comprising means for maintaining the carton with the wall being exposed,

shoe means having a leading nose portion,

means for relatively moving the shoe means with re-

spect to the carton for projecting the nose portion under the wall,

blade means secured to the shoe means rearwardly of the nose portion and extending laterally beyond the nose portion for entry between the two flaps to sever any releasable connection therebetween,

and means forming part of the shoe means positioned rearwardly of the blade in the path and having surfaces that flare divergently outwardly beyond the path for engaging and reversely bending the opened flaps.

11. A device for operating upon a carton having a pair of spaced side walls and a connecting wall formed by a flap of each side wall being bent to converge and have portions overlying each other that are releasably secured together to separate said flaps to open the carton, one of said flaps being wide and the other narrow;

comprising means for longitudinally guiding a carton along a path with the wall being exposed,

shoe means positioned in the path and having a leading nose portion aligned with the path and projectable under the wide flap,

blade means secured to the shoe means rearwardly of the nose portion and being formed to provide a thin front edge that extends laterally and rearwardly from the nose portion and an upper surface that flares upwardly as it extends rearwardly from the nose portion for entry between the two flaps to sever any releasable connection therebetween and to urge opening of the flaps,

and means forming part of the shoe means positioned rearwardly of the blade in the path and having surfaces that flare divergently outwardly beyond the path for engaging and reversely bending the opened flaps.

12. A device for operating upon a carton having a pair of spaced side walls and a connecting wall formed by a flap of each side wall being bent to converge and have portions that overlie each other that are releasably secured together,

means for guiding a carton along a path with the connecting wall being exposed,

means for separating the two flaps of the top wall by shoe means overlying the path and projectable beneath the connecting wall upon relative movement between the carton and shoe means,

said shoe means including a blade secured to the shoe means and having a thin front edge that extends substantially laterally of the path to enter between the overlying portions of the two flaps to sever any releasable connection therebetween,

and means for reversely bending the flaps to project outwardly from the side walls and including a first surface formed on the shoe means rearwardly of the blade that flares laterally as the shoe means extends rearwardly of the path for reversely bending one flap and another surface formed on the shoe means rearwardly of the blade that flares oppositely laterally as the shoe means extends rearwardly of the path.

13. A device for operating upon a carton having a wall formed by a wide flap overlying and releasably secured to a narrow flap to separate said flaps and open the carton comprising means for longitudinally guiding each carton along a path,

means for opening said flaps and including blade means having a thin front edge that extends substantially laterally of the path to enter between the overlying portions of the two flaps to sever any releasable connection therebetween and to urge the flaps to an open position,

blocking means normally positioned in said path for preventing movement of a carton therewith but movable therefrom to a non-blocking position to permit movement of a carton therethrough,

means positioned in said path after the blade means for

sensing the orientation of the wide and narrow flaps, and means mechanically interconnecting the blocking means and the sensing means for moving the blocking means to its non-blocking position upon the sensing of only the opening and correct orientation 5 of the wide and narrow flaps.

14. A device for operating upon a carton having a wall formed by a wide flap secured to a narrow flap to separate said flaps and open the carton:

comprising means for longitudinally guiding each car- 10 ton along a path,

means for opening the flaps and urging them upward- 15 ly in the path and including blade means positioned in said path and being formed to provide a thin front edge that extends laterally and rearwardly and an upper surface that flares upwardly as it extends rearwardly for entry between the overlying portion of the two flaps to sever any releasable connection therebetween,

blocking means normally positioned in said path for 20 preventing movement of a carton therpast but movable therefrom to a non-blocking position to permit movement of a carton therethrough, wide flap sensing means positioned in said path after the blade means and mounted for movement upon 25 engaging only the wide flap,

flap sensing means positioned in said path after the wide flap sensing means and mounted for movement upon engaging either flap,

blocking means interconnecting the wide flap sensing 30 means and the flap sensing means for preventing movement of the flap sensing means upon movement of the wide flap sensing means,

and means mechanically interconnected to the flap sensing means and the first mentioned blocking means for moving the latter to its non-blocking position upon movement of the flap sensing means.

15. A device for operating upon a carton having a wall formed by a wide flap releasably secured to a narrow flap to separate said flaps and open the carton;

comprising means for longitudinally guiding said car- 40 tons along a path,

means for opening the flaps and urging them upwardly in the path and including blade means positioned in said path and being formed to provide a thin front edge that extends laterally and rearwardly and an upper surface that flares upwardly as it extends rearwardly for entry between the overlying portion of the two flaps to sever any releasable connection therebetween,

a first arm pivoted for movement on one side of the path after the blade means for movement in the path,

a second arm pivoted for movement in and out of the path after the first arm and on the same side of the path, said first arm being spaced higher in the path than the second arm,

blocking member mounted for movement in and out of the path after the second arm,

linkage interconnecting the blocking member and the second arm whereby movement of the second arm out of the path moves the blocking member out of the path,

interfering means connected to the first arm and mounted for movement to an interfering position by movement of the first arm rearwardly to prevent movement of the second arm,

and means positioned rearwardly of the blocking member in the path and having surfaces that flare divergently outwardly beyond the path for engaging and reversely bending the opened flaps of a carton that has passed by the blocking member.
